UNITED STATES PATENT OFFICE

REGINALD GEORGE SALMON, OF BARKINGSIDE, ENGLAND, ASSIGNOR OF ONE-HALF TO
THE BRITISH STEEL PILING COMPANY, LIMITED, OF LONDON, ENGLAND, A CORPO-
RATION OF GREAT BRITAIN AND NORTHERN IRELAND

PILE DRIVER

Application filed October 30, 1931, Serial No. 571,992, and in Great Britain December 16, 1930.

This invention relates to pile drivers and more particularly to drivers for steel plate piling.

Heretofore, the driving of steel plate piles has necessitated the driving hammer which weighs, for example, three tons, being laid upon its side whilst a pile is secured to an attachment of the hammer in such a manner that the pile is held in a definite position relatively to the hammer. The hammer and pile are thereafter raised and swung into position for driving the pile. The piles are often sixty feet in height and the operation described takes a relatively long period of time so that the number of piles which it is possible to drive in one hour is relatively small and rarely exceeds four in number.

The improved pile driver according to this invention comprises a driving hammer, or an adaptor arranged to be carried by a hammer, having a bifurcated lower end, and suspension means arranged to connect a pile to the hammer or adaptor in such a manner that as the pile is raised from a substantially horizontal position, the upper end thereof swings automatically into position within the bifurcation so that the pile assumes a substantially definite upright position relatively to the hammer.

A constructional example of the improved pile driver is illustrated as to the relevant parts in the accompanying drawing, in which

Fig. 1 is a front elevation of the improved pile driver in lowered position for raising one end of a pile to be driven, showing also in dotted lines the successive positions relatively to the hammer into which the pile comes as the hammer is raised;

Fig. 2 is a side view at right angles to Fig. 1, the pile to be raised and driven being omitted;

Fig. 3 is a partly sectional plan on the line III—III of Fig. 2 showing also in dotted lines a pile in position to be driven and interlocked on one side with a pile already driven and on the other side with a standing pile about to be driven.

Referring to the drawing, in the construction illustrated an adaptor is used with the

pile driving hammer and is connected with the hammer as follows.

The framework of the adaptor is formed by four straight vertically disposed channel steel members 1, 2, 3, 4 which are bolted around the hammer casing. The upper end of the hammer casing terminates in the top plate 5 formed integral with the lifting eye 6, while the lower part of the hammer casing terminates in the corner legs 7, 8, 9, 10 (Fig. 3) and the anvil 11 (Fig. 1). The steam chest of the hammer is seen at 12 and the exhaust pipe at 13. The top ends of the steel channels 1 and 2 are riveted to the cross-brace 14 and the top ends of the channels 3 and 4 are riveted to the cross-brace 15, braces 14 and 15 being secured to the hammer casing by the bolts 16 and 17 respectively (Fig. 1).

A bifurcated jaw member formed of steel plate and channel members is secured to the lower ends of steel channels 1-4 which extend below the contact face of the anvil 11. This bifurcated member is formed of upwardly extending channel portions 18 and 19, of which the member 18 is secured on one side to the steel channel 1 by upper and lower stiffening plates 20 and 21 and on the other side to steel channel 2 by similar stiffening plates of which the upper one only is seen at 22 in Fig. 3, while the member 19 is secured on one side to the steel channel 3 by upper and lower stiffening plates 23 and 24 and on the other side to steel channel 4 by similar stiffening plates of which the upper one only is seen at 25.

A part of the lower stiffening plate 24 is cut away as shown in Fig. 1 and the corresponding lower stiffening plate (which does not appear in the drawing) connecting the channel member 19 to the vertical steel channel 4 is also cut away in a similar manner, so that one side 26 of the lower portion of the bifurcation is inclined away from the other side in a downward direction so as to form a "bird-mouth" opening 27. The arrangement is such that the bifurcation has two parallel sides 28, 29 disposed at right angles to the face of the anvil 11, and when the adaptor is secured in position upon a driving hammer

the striking face of the anvil 11 is located just clear, for example, by about one inch, of the upper open end 30 between the parallel portions 28, 29 of the bifurcation. The hammer and adaptor are permitted to move relatively to the end of a pile which has been located in the said bifurcation for the hammer to strike the end of the pile as this passes through the said upper end 30 of the bifurcation.

Transversely disposed members 31, 32 are secured upon opposite sides of the frame structure of the adaptor and holes are provided in the said members to enable hooks or loops such as shown at 33 and 34 secured to the ends of chains 35 and 36 respectively to be connected to the said members 31 and 32. The other ends of the chains 35, 36 are connected by loops such as indicated at 37 to a clamp or clip 38 which is firmly bolted to the pile 39 so that the chains form the suspension means between the adaptor and the pile.

The clamp 38 preferably comprises two steel bar members 40, 41 each lined with a hard wood block, one member 40 having the configuration of the inner cross-section of the steel pile 39 to be driven and the other member 41 having the configuration of the outer cross-sectional configuration of the pile, or a purely flat face as shown. The members 40, 41 of the clamp 38 are placed in position upon opposite sides of the pile 39 and firmly secured thereto by means of bolts 42 arranged to extend through the two clamp members 40 and 41. The upper bar 40 is provided with eyes upon its two ends whereby the aforesaid chains 35 and 36 may be secured to the clamp, for instance by loops such as shown at 37.

The position of the clamp 38 relatively to the upper end of the pile 39 to be driven is determined according to the length of the pile and so as to ensure that the upper end of the pile will swing automatically into the "bird-mouth" 27 of the bifurcated jaw member when the adaptor and pile connected thereto are lifted with the striking hammer in a manner which will now be described.

The operation of the pile driver is as follows:—

After the clamp 38 has been secured in position upon the pile 39 lying in a substantially horizontal position upon the ground, the hammer and adaptor are lowered by a crane or the like by means of the lifting eye 6 so that the bifurcated end thereof is disposed adjacent to that end of the pile which is to be driven, for instance the right hand end as shown in Fig. 1. The adaptor is connected to the clamp 38 by means of the chains 35, 36 and the hammer and adaptor are then raised to lift the pile 39 clear of the ground, whereupon the upper end swings into the "bird-mouth" 27 of the bifurcation so as to clear the inclined face 26 and becomes located with-

in the space between the two parallel faces 28, 29 of the bifurcation. The hammer and adaptor together with the pile are then swung into the desired position and the complete assembly lowered. As soon as the weight of the pile is taken by the material into which it is to be driven and/or by its locking engagement with the preceding pile, the hammer and adaptor move downwardly relatively to the pile which then extends into the space between the vertical parallel faces 28 and 29 of the bifurcation until the upper end of the pile contacts with the striking face of the anvil 11. Further downward movement of the pile is then effected by virtue of the weight of the hammer and when this downward movement ceases the usual striking operations of the hammer are commenced to drive the pile. During this operation the parallel faces 28, 29 of the bifurcation are reciprocated relatively to the upper end of the pile.

If the upper end of the pile is located at a comparatively great height from the ground during the initial part of the driving operation, the removal of the clamp 38 and chains 35, 36 may be effected after the pile has been driven a certain amount so as to bring the clamp into a convenient position for removal.

It will be appreciated that when the pile is swung into position so that the upper end thereof is located in the "bird-mouth" portion 27 of the bifurcation, the distance between the upper end of the pile and the striking face of the anvil 11 provides sufficient slack in the connecting chains to allow for the striking operations of the hammer to be effected.

It will be observed from the foregoing description that a pile driver constructed in accordance with this invention enables a pile to be connected to the striking hammer, swung into position for driving, and the driving operations commenced, with a minimum expenditure of time and labour. In actual practice it is found possible to drive a relatively much greater number of piles in an hour than heretofore.

When the adaptor above described is employed for driving steel piles of a corrugated or other angular or curved cross-sectional configuration, the various members forming the bifurcation are shaped to correspond therewith or to clear the edges of the pile. Further, when driving hammers of the usual type are employed in which an anvil block is located upon the bottom face of the hammer and is confined between four legs located at the corners of the underside of the hammer and extending below the face of the anvil block, it may be necessary to cut away a portion of some or all of the legs to clear the side of the pile being driven or to clear the

upper ends of the next adjacent pile or piles which have already been driven.

Instead of the adaptor described above a hammer may be constructed according to the invention with a "bird-mouth" bifurcation formed integrally therewith or with the anvil block thereof.

Further, it is to be understood that modifications in the form of the bifurcation may 10 be made to accommodate various piling sections which it is desired to drive.

It is also to be understood that the above described suspension means for connecting a pile to be driven to the hammer or adaptor 15 may be variously modified, for example, links and lost motion devices may be provided in lieu of the chains, the lost motion devices enabling the strokes of the hammer relatively to the pile to be effected. The construction of the clamp 38 may also be modified 20 and may comprise any automatically acting type of gripping device.

What I claim and desire to secure by Letters Patent is:—

25 1. Pile driving apparatus for steel plate piling, comprising a driving member, means for suspending, lowering, and raising the driving member, an anvil face on the driving member, two jaw members projecting beyond 30 and at right angles to the anvil face and forming a recess between them, and a connection between the pile to be driven and the driving member enabling the operation of raising the driving member from its lowered position to simultaneously move the pile from a 35 recumbent position on the ground into an upright position with the driven end inserted in the recess between said jaw members ready to be driven.

40 2. Pile driving apparatus for steel plate piling, comprising a driving member, a bifurcated lower end of the driving member, means for suspending the driving member, lowering it from and raising it to its operative 45 position, and means for attaching a pile while in a substantially horizontal position on the ground to the driving member in its lowered position such that the operation of raising the driving member from said position into driving position simultaneously 50 raises the pile and causes the driven end of the same automatically to enter the bifurcation at the lower end of the driving member in position for the driving operation.

55 3. Pile driving apparatus for steel plate piling, comprising a driving member, a bifurcated lower end of the driving member, means for suspending the driving member, lowering it from and raising it to its operative 60 position, and a connection between the driving member and a pile lying on the ground such that the movement of the driving member from its lowered to its operative position moves the driven end of the pile 65 into the bifurcation at the lower end of the

driving member and allows the pile automatically to swing into position to be driven.

4. Pile driving apparatus for steel plate piling, comprising a driving hammer, and an adaptor constructed around the driving hammer casing, the adaptor consisting of interconnected angle steel members having ends extending beyond the anvil of the hammer, and stiffening plates connected to the extended ends of the angle steel members arranged to form between them a comparatively narrow passage having parallel sides directed at right angles to the face of the anvil, and means connecting the adaptor to a pile for bringing the driving end of a pile into driving position within the said narrow passage.

70 5. Pile driving apparatus for steel plate piling, comprising a driving hammer and an adaptor constructed around the driving hammer casing, the adaptor consisting of four interconnected angle steel members forming the parallel corners of an elongated rectangular frame extending beyond the anvil of the hammer, a stiffening structure connected between the extended ends of two adjacent corner members of the said rectangular frame, and another stiffening structure connected between the extended ends of the other two adjacent corner members of the said rectangular frame, the two stiffening structures forming between them a comparatively narrow passage having parallel sides directed at right angles to the face of the anvil 80 of the hammer and adapted to receive between them the driving end of a pile.

85 6. Pile driving apparatus for steel plate piling, comprising a driving hammer and an adaptor constructed around the driving hammer casing, the adaptor consisting of four interconnected angle steel members forming the parallel corners of an elongated rectangular frame extending beyond the anvil of the hammer, a stiffening structure connected between the extended ends of two adjacent corner members of the said rectangular frame, and another stiffening structure connected between the extended ends of the other two adjacent corner members of the said rectangular frame, the two stiffening structures forming jaw members of a bifurcation adapted to engage the driving end of a pile, and the outer end of one jaw member being inclined away from the other jaw member.

90 105 110 115 120 125 130 7. The method of bringing a sheet metal pile from a recumbent position on the ground into and retaining said pile in driving position relative to a pile driver, which consists in lowering the pile driver by the usual means (such as a crane) to a position approximately vertical over the end of the recumbent pile to be driven, attaching the pile driver while suspended vertically in said position to the recumbent pile by means

slings) connecting points on opposite sides of the pile driver at a predetermined distance above the anvil face of the latter to points on opposite edges of the pile at a predetermined distance from the driving end thereof, and vertically raising the pile driver and attached pile to allow the driving end of the pile to swing automatically into a prepared bifurcation provided on the lower end of the pile driver so as to dispense with the necessity for laying the driving hammer on its side while securing the pile to an attachment of the hammer.

8. A method of bringing a sheet metal pile from a recumbent position on the ground into and retaining said pile in driving position relative to a pile driver, which consists in lowering the pile driver to a position over one end of the recumbent pile, attaching the pile driver while suspended to one end of the recumbent pile by means connecting points on opposite sides of the pile driver at a predetermined distance above the anvil face of the latter to points on opposite edges of the pile at a predetermined distance from the driving end thereof, and vertically raising the pile driver and attached pile to allow the driving end of the pile to swing automatically into a prepared bifurcation provided on the lower end of the pile driver so as to dispense with the necessity for laying the driving hammer on its end while securing the pile to an attachment of the hammer.

In testimony whereof, I affix my signature.
